UNITED STATES PATENT OFFICE.

EARL A. AVERILL, OF MOUNT VERNON, NEW YORK, ASSIGNOR TO LOCOMOTIVE FEED
WATER HEATER COMPANY, A CORPORATION OF DELAWARE.

MEANS FOR PROTECTING PRESSURE GAUGES ON FLUCTUATING-PRESSURE WATER LINES.

1,424,145.

Specification of Letters Patent. Patented Aug. 1, 1922.

Application filed May 8, 1920. Serial No. 380,013.

To all whom it may concern:

Be it known that I, EARL A. AVERILL, a citizen of the United States, residing at Mount Vernon, in the county of Westchester 5 and State of New York, have invented certain new and useful Improvements in Means for Protecting Pressure Gauges on Fluctuating-Pressure Water Lines, of which the following is a specification.

10 This invention relates to the provision of means for protecting the mechanism of a pressure gauge connected to the discharge side of a water pump which is subject to wide fluctuations in pressure conditions. It 15 is particularly useful in connection with gauges which are used in association with the boiler feed pump of a locomotive and in connection with this description I have illustrated my invention in such an association.

In locomotive practice as it has heretofore existed, it has been customary to install a needle valve just below the pressure gauge in the engine cab which gives the 25 readings of the pressure conditions in the discharge line of the boiler feed pump. These pressure conditions fluctuate within wide ranges and are frequently quite violent, and the needle valve has been necessary to 30 protect the mechanism of the gauge which would otherwise be seriously damaged by the water hammer. The adjustment of such a needle valve must be very close and the opening through it is so fine that it very 35 easily clogs with a slight bit of scale or dirt. When this occurs the valve must be opened and cleaned and then reset all of which consumes time and increases the expense of maintenance.

40 It is the particular object of my invention to provide adequate protection for the gauge without the necessity of using a needle valve such as has heretofore been considered necessary. Specifically my 45 invention consists in the provision of an air chamber on the pressure gauge pipe connection.

The invention and its objects will be more clearly understood upon reference to the accompanying drawing, wherein the figure is 50 a diagrammatical side elevation of a locomotive with my improvement illustrated in

association with the discharge side of the boiler feed pump.

The boiler feed pump 1 discharges water 55 through the pipe 2 into a feed water heater 3 from which it enters the boiler 4 through the pipe 5 and the boiler check valve 6. The pump is connected to the supply receptacle or tender, not shown, by means of 60 the pipe 7, said pipe constituting the suction line of the pump. The pump is actuated by means of live steam admitted through the pipe 8 and discharged through the pipe 9. 65

Within the cab 10 is located the pressure gauge 11 which communicates with the discharge pipe 2 of the boiler feed pump through the connection 12. Beyond the gauge at the end of the pipe 12 is located 70 an air chamber 13.

Immediately below the gauge at the point marked 14 it has heretofore been customary, as above pointed out, to introduce a needle valve for the purpose of protecting the 75 mechanism of the gauge against water hammer damage due to the wide fluctuations in the pressure conditions existing in the discharge line of the pump. By providing the air chamber 13 I have found that this needle 80 valve can be entirely dispensed with. The air chamber very adequately prevents damage to the gauge while at the same time permitting an accurate reading of the pressure as well as an indication of the pulsations. 85 In installations of this kind, the pulsations of the hand on the gauge are as much a part of the required indication as the actual position of the hand and both of these are permitted by the protection scheme afforded 90 by the air chamber. The air chamber softens the blow, but does not eliminate it entirely, but only sufficiently to prevent damage to the instrument.

The foregoing arrangement is particularly 95 advantageous in locomotive practice. On a locomotive, because it is essential that as small and light a piece of apparatus be used as will adequately meet the requirements, the pump is operated at speeds which 100 are higher than would obtain in stationary pump practice. Furthermore the air chamber capacity on the line is of necessity limited. Under these conditions, the ar-

angement above disclosed proves of exceptional value.

I claim:

5 The combination with a locomotive boiler feed pump of a pressure gauge connected to the discharge side of the pump and an air chamber associated with said gauge,

said chamber opening into the connection which extends from the discharge side of the pump to said gauge whereby to prevent 10 damage to the gauge.

In testimony whereof I have hereunto signed my name.

EARL A. AVERILL.
